L. A. FRYE

TRUSSED GIRDER

Original Filed May 18, 1920

UNITED STATES PATENT OFFICE.

LEWIS A. FRYE, OF LOS ANGELES, CALIFORNIA.

TRUSSSED GIRDER.

Application filed May 18, 1920, Serial No. 382,448. Renewed June 11, 1923.

This invention relates to a trussed girder and more particularly to a continuous trussed girder; and an object of the invention is to provide a continuous trussed girder structure which is particularly strong and rigid for its size and weight yet simple and inexpensive.

The invention is particularly applicable to structures for suspended or elevated railway systems although it will be understood that it is not in any way restricted to such specific application. In the present disclosure of the invention it is applied to a structure for carrying a rail adapted to carry suspended monorail cars.

A particular feature of the invention is the manner in which the sections, or girders, are connected and trussed so that they are exceptionally strong and rigid. The strength and rigidity obtained by the present invention are particularly advantageous for structures of the character above specified.

Other objects and features of the invention will be best understood from the following detailed description of a preferred embodiment of the invention throughout which reference is had to the accompanying drawings, in which—

Fig. 1 is a side elevation of a trussed girder as provided by the present invention; Fig. 2 is an enlarged side elevation of a portion of the girder showing the manner in which the truss rods are spaced from the girder; Fig. 3 is an enlarged detailed sectional view taken as indicated by line 3—3 on Fig. 1; Fig. 4 is a detailed sectional view taken as indicated by line 4—4 on Fig. 3; and Fig. 5 is a side elevation of the parts shown in Figs. 3 and 4 being a view taken as indicated by line 5—5 on Fig. 4.

Throughout the drawings numerals 10 designate I beams arranged end to end and tied, or connected, together by channels 11 and angles or channels 12. The I beams 10 may be, and preferably are, standard I beams and have a plate 13 riveted or otherwise suitably secured to their upper flanges 14. The plate 13 forms a member or base on which to mount the cup, or U-shaped, rail 15 and also strengthens the structure laterally when it is made comparatively wide as shown in the drawings.

The channel members 11, of which there is one at each I beam connection, are vertically disposed, or arranged at right angles

relative to the longitudinal axis of the I beams 10, and are arranged so that their webs 16 engage or seat against the webs 17 of the I beams, and so that they are between the flanges 14 and 18 of the I beams. The manner in which the channels 11 are arranged in connection with the I beams 10 is clearly illustrated in Figs. 4 and 5 of the drawings. It will be noted in these figures of the drawings that the channel 11 is secured to each of the abutting beams 10 by rivets 20 thereby positively and securely connecting them. It will be understood, of course, that any suitable number of rivets 20 may be employed to connect the I beams and channels 11 in order to make the connection sufficiently strong and rigid.

At each beam connection two channels 12 are arranged, on the opposite side of the web 17 to that at which the channels 11 are arranged, in order to form a tie or connection between the abutting I beams in substantially the same manner as does the channel 11. The channels 12 are arranged so that their webs 21 engage or seat against the webs 17 of beams 10, and are spaced somewhat apart so that the web 22 of supporting beam 23 will fit between their adjacent flanges 24, as shown in Fig. 4. The particular supporting beams 23 herein shown, are comparatively large, or heavy, horizontally disposed I beams, but it will be understood that the invention is not in any way limited to any one specific form of supporting members. The flanges 24 and web 22 are connected together by suitable rivets 25 thereby making the two channels 12 practically a solid or continuous member. The webs 21 of the channel members 12 are secured to the webs 17 of I beams 10 by rivets 20, as clearly shown in Figs. 3 and 4, thereby causing the two channel members 12, or the structure formed by the two channel members 12, to co-operate with the channel 11 in tying or connecting the I beams 10 together. The I beams 10, being thus tied or secured together by the channels 11 and channels 12, form a continuous structure having a point of support at each beam connection.

To reinforce, or truss, the structure formed by the I beams 10 to make it strong and rigid, truss rods 27 are arranged between the flanges 28 of adjacent channels 11 and between adjacent flanges 29 of channels 12. This arrangement of truss rods 27

causes each I beam 10 to be trussed by two rods. The truss rods 27 in connection with each I beam 10 each extend over two spacers or struts 30 which extend downwardly from the flange 18 of the beam as clearly shown in Figs. 1, 2 and 3. The struts 30 are each arranged from the ends of the beam at a distance equal to approximately one third of the total length of the beam. Each strut 30 comprises a wooden block 31, secured to the flange 18 by suitable angle irons 33, as clearly shown in the drawings, and a plate or saddle 34 mounted on the outer end of the block 31. The saddle 34 has hooks 35 formed at opposite sides to carry the truss rods 27, as clearly shown in Figs. 2 and 3. The ends of the truss rods 27 extend through the flanges 28 and the flanges 29 and carry nuts 36. Suitable wedge shaped washers 37 are arranged under the nuts 36, which are on the rods that extend through flanges 28, so that the nuts will have a flat suitably disposed surface on which to seat. The washers 37 are shaped to compensate for the angularity at which the rods 27 extend through the flanges 28, caused by the arrangement of the rods over the spacers 30, and also the angularity of the inner faces 38 of flanges 28. Suitable wedge shaped washers 39 are arranged under the nuts 36, on the rods which extend through flanges 29 so that the nuts will have a flat suitably disposed surface on which to seat. In the constructions shown in the drawings the channels 12 are formed of even thickness throughout so that the washers 37 need only compensate for the angularity at which the rods 27 extend through the flanges 29.

A turn buckle 40 is arranged in each truss rod 27, intermediate of its two ends so that it can be tightened or put under tension. When the truss rods 27 are put under tension they tend to draw the channels 11 together and to draw the channels 12 together thereby causing the I beams 10 to be put under compression, or in other words, causing the beams 10 to become compression members. When a load comes upon an I beam 10 at any point, or points, between its two ends, the beam tends to flex or bend downwardly and thereby causes increased tension to come upon rods 27 which thereupon cause increased compression to come upon the I beam 10 greatly increasing its ability to resist the forces acting upon it. In practice, when the truss rods 27 are under the proper tension, a load, or pressure, upon the beam 10 will cause practically no flexure or bending of it.

60 The truss rods 27 of adjacent I beams 10 are secured or tied together by the channels 11 and the channels or angles 12 thereby causing the truss rods to be practically continuous, and causing strain to be transferred between adjacent truss rods through the

channels 11 or the channels 12. Further, part of the strains in the truss rods, supporting any one particular I beam, are also transmitted to the adjacent beams through the channels 11 and channels 12 due to the channels being secured to the beams. The strains or forces in any one I beam 10 and its truss rods 27, are partially transmitted or distributed to adjacent I beams and truss rods thereby preventing concentration of strains on any one member or section of the structure. In other words, the construction is continuous and such that a load on any one particular I beam sets up forces in that I beam which are distributed through the entire structure and particularly into the adjacent I beam and their truss rods.

It will be noted in the drawings that the saddles 34 and blocks 35, which carry the truss rods, are spaced considerable distance apart, in fact, so that they are outward of the outer edges of the flanges 18. Further, the flanges 28 and 29 are comparatively short and do not extend outwardly beyond the flanges 14 and 18. The flanges 28 and 29 being short cause the ends of the truss rods to be secured close to the web 17 of beams 10, while the hooks 35 being spaced both downwardly and outwardly from the beam cause the middle portions of the truss rods to be both below and outwardly from the beams. As has been before stated the truss rods by being arranged below the beams strengthens them against downward flexure or bending; in a like manner the arrangement of the truss rods outwardly from the beams greatly strengthens them against lateral flexure or bending. With the arrangement of truss rods just described the ends of the truss rods are not only arranged close to the webs 17 but are also arranged close to, or immediately below the flanges 14. The arrangement of the ends of the rods close to the flanges 14 causes the forces, from the truss rods tending to compress the beams to be applied directly to the upper portions of the beams where they are most effective.

Having set forth a preferred embodiment of my invention I do not wish to limit myself to the specific details hereinabove set forth but wish to reserve to myself any changes or variations that may appear to those skilled in the art or that may fall within the scope of the following claim.

Having described a preferred form of my invention, I claim:—

In combination, a plurality of beam members meeting end to end, support members for the beam members at their points of meeting, members connecting the beam members to the support members and also connecting the opposed ends of adjacent beam members at top and bottom in a manner

to form a continuous beam, vertical flanges on the connecting members and which extend laterally from the side faces thereof, and a truss member associated with each beam member, each truss member extending below its associated beam member between the supporting members and being terminally se-

cured to the flanges of the connecting members at points above the neutral axis of the beam.

In witness that I claim the foregoing I have hereunto subscribed my name this 4th day of May 1920.

LEWIS A. FRYE.
